VALVE TESTING CLAMP

Carl P. Freudenberg, Chicago, Ill.

Application July 22, 1931, Serial No. 552,534

2 Claims. (Cl. 73—51)

This invention relates to certain novel improvements in valve testing clamps, and has for its principal object the provision of an improved construction of this character which will be highly efficient in use and economical in manufacture.

For the purpose of inspecting and repairing the intricate mechanism of the so-called feed or reducing valves of a railway air-brake and control mechanisms, it is necessary to remove these valves from their operative position upon the locomotive or car. This invention is designed to provide a new and improved device for clamping these valves in such a manner that the repair and inspection of the valves will be facilitated and expedited.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a top plan view of the invention;

Fig. 2 is a side elevation view on line 2—2 in Fig. 1;

Fig. 3 is an end elevational view on line 3—3 in Fig. 1;

Fig. 4 is an end elevational view on line 4—4 in Fig. 2; and

Fig. 5 is a front elevational view of a plate customarily embodied in the type of valves with which the invention is used.

In the drawing, which illustrates a practical embodiment of the invention, one of the so-called feed or reducing valves upon which the invention is used, is indicated diagrammatically and generally at 10. These valve structures include a casing which includes a plate 12. In these plates 12, which are of standard construction, there is provided an air inlet port 13 and an outlet port 14 through which air may be introduced into the casing 11 so as to act upon the valve structures therein for the purpose of testing the same.

Likewise provided in this plate 12 is a pair of recesses 15 which assist in mounting the valve 10 upon the clamp provided by this invention, and generally indicated at 16.

The clamp 16 includes a stationary jaw 17 and a movable jaw 18 which is hinged, as at 19, to one part 20 of the base generally indicated at 21 and composed of the part 20 and the foot 22 of the stationary jaw 17. The parts 20 and 22 are detachably connected by bolt and nut structures

23, and apertures 24 are provided in the base 21 so that screws or the like may be passed there-

through to fasten the clamp upon a work table or other support.

Extending through apertures provided in the jaws 18 and 17 is a bolt 25 which has a head 25' having a pressed fit in the recess 51 in jaw 18 and this bolt has a threaded stem 26 upon which is mounted a sleeve 27 that has a threaded internal bore 28 into which the stem 26 is threaded. Carried by the sleeve 27 is a handle structure 29 including the arm 30. Two springs 31 extend between the jaws 17 and 18 and have their ends fitted in recesses therein. It is apparent, therefore, that by turning the handle 30 and sleeve 27 counterclockwise as seen looking in from the right side of Fig. 2, the sleeve 27 will be retracted upon the bolt and the springs 31 will urge the jaw 18 away from the jaw 17, the jaw 18 pivoting at 19, the sleeve 27 being prevented from coming off the bolt by a stop pin or dowel 49 adapted to engage the head 50 of the bolt.

On the upper end of jaw 18 is a step 32 from which projects upwardly a pair of spaced apart ears 33, between which is a well 36, for reasons to be made apparent hereinafter. Adapted to project over the step 32 is a flange or head 34 that is provided on the upper end of jaw 17, and on the side of this head 34 that faces toward the ears 33 is a pair of spaced apart lugs or dowels 35.

Extending through the head 34 is an air inlet passage 37 to which is connected an air conduit 38 that is provided with a suitable control valve 39. An air outlet passage 40 is likewise provided in the head 34 and connected to this passage is an air outlet conduit 41 that is provided with a nozzle 42 and a control valve 43.

In the use of the invention, the valve 10 is placed in the position shown diagrammatically in Figs. 1 and 2, so that the plate 12 will rest on the step 32, in the manner shown in Fig. 2, a part of the valve casing lying in the well 36, between the ears 33. The handle 30 is then rotated to move the jaw 17 and its head 34 toward the ears 33 and the lugs 35 are then entered in the recesses 15 in the plate 12, thereby holding the valve 10 in position on the clamp and aligning the passages 37 and 40 with the ports 13 and 14. The valve 39 is then opened to permit air under pressure to flow through conduit 38 and passage 37 into the valve inlet port 13 so as to test the mechanisms in the valve 10, the air leaving valve 10 and its casing 11 by way of port 14, from which the air will flow by way of conduit 41 and out of the nozzle 42, valve 43 being opened.

Experience in the use of the invention on locomotive feed or reducing valves teaches that

if the slide valve, and regulating valves and piston in the valve structure 10 are in proper working order the air emerging from the casing 10, and passing by way of outlet conduit 41, will pulsate or flow intermittently and rhythmically from the nozzle 42 while, on the other hand, if the slide valve, regulating valves and piston in valve structure 10 are not in proper working condition the air passing out of the casing 11 will flow from the nozzle 42 in a continuous, uninterrupted stream. Thus, a mechanic skilled in the art will be apprised of the condition of the mechanism in the valve 10 and be informed of the repairs needed thereby, if any, without the necessity of placing the feed valve in valve structure 10 on a standard test rack to determine the condition of the same, as has been the practice heretofore in the art. Moreover, the clamp will hold the feed valve 10 securely and firmly while the slide and regulating valve seats therein are reseated so that any leaks in either the slide or regulating valves may be corrected without removing the feed valve 10 from the clamp. To those skilled in the art it will also be apparent that the clamp will enable the mechanic to determine whether or not the supply valve piston has the proper fit to pass what is known as the "range test" on a standard test rack.

Provided in the jaw 17 is a hole 44 that is aligned with the well 36 (Fig. 4) and this arrangement of hole 44 and well 36 permits the mechanic to insert a file therethrough for the purpose of filing the slide valve seat in the valve structure 10 without removing the same from the clamp.

In the use of the valves 10 the plates 12 sometimes become worn on the face thereof that is disposed toward the head 34 and at the left side thereof, as seen looking in from the left in Fig. 1, thus rendering it difficult to obtain an air tight seal between the passages 37 and 40 and the ports 13 and 14. To overcome this difficulty, I provide a shim 45 which is hinged, as at 46, to a bracket 47 that is fastened to the left side of jaw 18, as seen from the left in Fig. 1. When the plate 12 is worn, as above described, the shim 45 may be swung up into position between the worn face of plate 12 and the face 48 of head 34, so as to effect an air tight seal between the passages 37 and 40 and the ports 13 and 14.

Before applying the spring box to the feed valve the condition of the regulating valve and supply valve in the valve structure 10 can be ascertained, and if either is leaking it may be repaired without removing the valve 10 from the clamp, after which the spring box may be applied and the condition of the piston may be as-

certained by screwing up on the regulating nut or hand wheel. If the feed valve pulsates it indicates that the feed valve is ready for final test and the required pressure setting, thereby practically eliminating the applying of the feed valve to, and removal of it from, the standard test rack several times which has heretofore been the necessary and customary practice in the art.

From the foregoing description it will be apparent to those skilled in the art that the invention provides a clamp which will facilitate and expedite the testing and conditioning of feed or reducing air valves of the character described.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A valve testing clamp, comprising a pair of adjustably associated clamping members, one of said clamping members including a step portion and a pair of spaced elements projecting above said step portion, the other of said clamping members including a head portion projecting over said step portion and provided with passages, spaced lugs on said head portion, a conduit communicating with each of said passages, and means for moving said clamping members relative to each other.

2. A valve testing device comprising a base, adjustably associated upright clamping members rising from the base, one of said members being fixed and the other pivoted with respect to the base, a step for the pivoted member and provided with a well, spaced ears rising from the free end of the step upon opposite sides of the well for co-operation therewith and the step for receiving and supporting a portion of a valve to be tested, a head on the fixed member and extending at right angles with respect thereto for disposal above the step, said head having air passages therein, lugs extending from the head upon opposite sides of the air passages to be received in ports of the valve to align passages of the latter with the passages of the head, and means including springs for adjusting said clamping members relative to each other.
